(57) **CLAIM**

The ornamental design for an earphone, as shown and described.

DESCRIPTION

FIG. 1 is a perspective view of an exemplary earphone.

FIG. 2 is a front view thereof.

FIG. 3 is a back view thereof.

FIG. 4 is a right side view thereof.

FIG. 5 is a left side view thereof.

FIG. 6 is a top view thereof; and,

FIG. 7 is a bottom view thereof.

The design is an earphone comprising a strap. The perimeter of the insert opening of the earphone is shown by broken lines in FIG. 3.

The broken lines depict environment and form no part of the claimed design.

1 Claim, 6 Drawing Sheets
